UNITED STATES PATENT OFFICE.

WILLIAM M. RYAN, OF CHICAGO, ILLINOIS, ASSIGNOR TO RYAN CAR COMPANY, OF CHICAGO, ILLINOIS, A CORPORATION OF MAINE.

RAILWAY-CAR.

1,069,729.

Specification of Letters Patent. Patented Aug. 12, 1913.

Application filed November 22, 1907. Serial No. 403,259.

To all whom it may concern:

Be it known that I, WILLIAM M. RYAN, a citizen of the United States, and a resident of Chicago, county of Cook, and State of Illinois, have invented certain new and useful Improvements in Railway-Cars, of which I do declare the following to be a full, clear, and exact description, reference being had to the accompanying drawings, forming part of this specification.

The present invention has more particularly for its object to provide an improved means for strengthening the under frame of wooden railway cars, and the invention consists in the features of novelty herein-after described, illustrated in the accompanying drawings and particularly pointed out in the claims at the end of this specification.

Figure I is a view in central vertical section through a portion of a railway car embodying my invention. Fig. II is a plan view of the parts shown in Fig. I, portions of the car floor being broken away. Fig. III is a view in vertical section on line 3—3 of Fig. I. Fig. IV is a view in vertical section on line 4—4 of Fig. I. Fig. V is a front elevation, parts of the car body being broken away. Fig. VI is a detail plan view of one of my improved draft sills with a portion of a thrust beam connected thereto. Fig. VII is a view in side elevation of the parts shown in Fig. VI.

1 designates the wooden body of a freight car and 2 denotes one of the cross-sills at the end of a car. Beneath the floor 3 of the car-body extend the longitudinal, intermediate sills 5 and the longitudinal, central sills 6 that run from end to end of the car. Beneath the central, longitudinal sills 6 and bolted thereto as at 7 is placed my improved draft sill that is formed as a single casting having side walls 8 and a top plate 9. The front portion of my improved draft sill is formed with a raised shoulder 10 adapted to sit behind the cross-sill 2 at the end of the car, and with a raised end portion 11 adapted to extend upwardly above the lower portion of the cross-sill 2. This raised portion 11 has a central strengthening web 12 (see Fig. VI) which extends between the upper and lower plates of the end portion of the casting. The front end of the casting is also formed with a chamber 15 that leads to the chambered portion 16 between the walls 8 of the body of the sill and within these

chambers 15 and 16 will be mounted the usual draw bar and the draft rigging leading back from the coupler head of the car. A plate 18, having upturned ends 19, is bolted as at 20 to the bottom of the head or end 11 of the draft sill and serves as a support for the draw bar. Between the laterally extending flanges 21 of the draft sill are formed strengthening webs or walls 22 which add to the strength and rigidity of the casting.

The rear portion of the draft sill is formed with a transverse chamber or pocket 25 to receive the bolster 26 of the car. Through the top wall 27 of the chamber 25, and through the top plate 9 above it, is formed an opening 29 to receive the king-pin whereby the draft sill and the bolster will be connected with the car truck. Beneath the chamber 25 at the rear of the draft sill extends the center plate 32 that is bolted as at 33 to the draft sill. The underside of the draft sill is adapted to interlock with the center plate 32. This is formed with flanges 40 and 41 against which the projectors 40^a and 41^a of the draft sill will bear. By thus forming interlocking parts between the draft sill and the center plate 32 the danger of shearing the bolts that connect the center plate to the draft sill is avoided, as the strains and thrusts to which the center plate 32 is subjected are borne in great measure by the flanges of the center plate. Moreover, the raised front and rear flanges of the center plate most effectively serve to prevent any buckling or spreading of the front and rear portions of the draft sill under the strains to which the parts are subjected.

At the rear end of the draft sill are preferably formed the contracted walls 45 and 46 constituting a pocket to receive one end of the thrust beam 47 which, as shown, is an ordinary I-beam, its end being riveted to the side walls 45 and 46, and its lower flange resting within the pocket at the base of these walls. It will be understood that the I-beam will run to the opposite end of the car that will be provided with a draft sill of a construction like that above described. By forming my improved draft sill of a single casting of the construction shown, it affords a most effective means for strengthening wooden freight cars, since the casting can be readily inserted beneath and between the center, longitudinal sills of the

car and, the casting being in a single piece, much more effectively resists the lateral and torsional strains to which freight cars are subjected in the severe usage to which they are exposed. By providing the shoulder 10 and the raised portion 11, at the front end of the draft sill, a pocket is formed to receive the cross-sill 2, the raised portions of the pocket holding the cross-sill against movement both in forward and backward direction. By providing the ends walls or plates 45 and 46 at the end of the draft sill, a most effective means is afforded for attachment to the end of the thrust beam, thereby most effectively guarding against any shearing action upon the rivets, incident to the torsional strains to which the parts are subjected.

My present invention affords a most effective means for strengthening the under frame of wooden railway cars since, by means of my invention, an exceedingly rigid and durable structure leading from end to end of the car is provided so as to take the shocks and strains to which railway cars, and particularly railway freight cars, are constantly exposed.

My invention is readily applicable to wooden cars of ordinary construction and, when applied thereto, will serve to most effectively prolong the life of the car.

Having thus described my invention, what I claim as new, and desire to secure by Letters Patent, is:—

1. The combination with the underframe of a railway car, of a metallic draft sill formed of a single casting and having a transverse pocket at its forward end and upon its upper face to receive a cross sill.

said draft sill also having upon its under side and at its rear, projecting flanges and one or more parts adapted to engage a center plate, and a center plate mounted beneath said draft sill and bolted to said flanges.

2. The combination with the underframe of a railway car, of a metallic draft sill having a transverse opening at its rear end to receive a car bolster and also having a raised top surface and a raised end portion forming a pocket to receive the cross sill of the car, and a cross sill located within and filling said pocket.

3. The combination with the underframe of a railway car, of a metallic draft sill formed as a single casting, having a raised portion at its outer end to engage the cross sill of the car and having at its inner end a pocket to receive the bolster of the car.

4. The combination with the underframe of a railway car, of a metallic draft sill formed as a single casting and provided at its inner end with integral, upwardly extending walls, and a thrust beam having its end located between said raised walls and secured thereto.

5. The combination with the underframe of a railway car, of a metallic draft sill formed as a single casting and having its inner end provided with integral, upwardly extending walls and a pocket formed at the base of said walls, and an I-beam having its ends secured between said walls with its base flange within said pocket.

WILLIAM M. RYAN.
